(57) **CLAIM**

The ornamental design for seating furniture, as shown and described.

DESCRIPTION

FIG. 1 is an isometric view of seating furniture in the form of an armless chair incorporating our new design;

FIG. 2 is a rear isometric view thereof;

FIG. 3 is a side, partially isometric view thereof;

FIG. 4 is a side elevation view thereof;

FIG. 5 is a front elevation view thereof, wherein the break lines indicate indeterminate length;

FIG. 6 is a top plan view thereof, wherein the break lines indicate indeterminate length;

FIG. 7 is a rear elevation view thereof, wherein the break lines indicate indeterminate length;

FIG. 8 is an isometric view of a loveseat embodiment thereof, wherein the break lines indicate indeterminate length;

FIG. 9 is a side, partially isometric view thereof, wherein the break lines indicate indeterminate length; and,

FIG. 10 is a front elevation view thereof, wherein the break lines indicate indeterminate length.

The broken lines shown in the drawings are for illustrative purposes only and form no part of the claimed design.

1 Claim, 6 Drawing Sheets
